UNITED STATES PATENT OFFICE.

ARTHUR J. WILKINS, OF BRISTOW, VIRGINIA.

RAIL-JOINT.

1,391,438.

Specification of Letters Patent. Patented Sept. 20, 1921.

Application filed March 5, 1920. Serial No. 363,476.

To all whom it may concern:

Be it known that I, ARTHUR J. WILKINS, a citizen of the United States, residing at Bristow, in the county of Prince William and State of Virginia, have invented new and useful Improvements in Rail-Joints, of which the following is a specification.

My present invention has reference to a means for connecting the confronting ends 10 of railway rails.

The primary object is to produce a means whereby the rail ends will be effectively connected and supported in a manner that will prevent vertical or independent side movement of the rails which would tend to bring the same out of alinement, and which will also permit of a limited longitudinal movement of the rails incident to expansion and contraction or to the pushing effect of the 20 wheels traveling thereover, means being provided, however, for preventing further movement thereof beyond the limited movement aforesaid, thus forming a rigid limit to movement equivalent to a direct contact 25 of the rail ends.

A further object is to produce a comparatively simple but practical and thoroughly effective rail joint.

Other objects and advantages will present 30 themselves as the nature of the invention is better understood, reference being had to the drawings accompanying this specification, in which there is illustrated a satisfactory embodiment of the improvement reduced to practice.

In the drawings:

Figure 1 is a top plan view showing two rails connected in accordance with this invention.

Fig. 2 is a side elevation thereof.

Fig. 3 is a similar view with parts in section showing the two rails separated by contraction.

Fig. 4 is a transverse sectional view approximately on the line 4-4 of Fig. 3.

Fig. 5 is a similar sectional view on the line 5-5 of Fig. 3.

Fig. 6 is a perspective view of the pivoted rail engaging member.

Fig. 7 is a similar view of the link which also provides a rail engaging member.

Fig. 8 is a side elevation of one of the rail ends.

Fig. 9 is a side elevation with parts in section showing the two rails at their nearest approach to each other.

In carrying out my invention, I preferably thicken the base of the rails 1, at the ends thereof. This may be done in the process of manufacture of the rails, but the 60 thickened portion may be also applied to an already constructed rail. The rails are of the usual formation, and the thickened base may be provided by swaging or welding a plate to the base of the rail. This thickened 65 portion is indicated by the numeral 2, in the drawings, and is provided, approximately at the center thereof with a depending lug 3. The lug has one of its ends rounded or 70 convexed in cross section, as indicated by the numeral 4, and its opposite end provided with a concaved transverse depression 5. The thickened base 2, adjacent to the inner 75 end thereof is approximately centrally formed with a depending ear 6, and this ear has a transverse opening 7 therethrough. While it is preferable to provide the rails at the ends thereof with the thickened base portion, as just described, it is to be understood that if desired the lug 3 and the ear 80 6 may be formed with or secured on the base flange of ordinary rails.

As disclosed by the drawings the ends of the rails 1 rest on a chair of a peculiar construction. This chair includes a flat base 8 85 that is provided at its ends with depending rectangular portions forming box-like pockets 9. The pockets open through the upper face of the base 8 and are otherwise closed. The outer ends of the box members that 90 provide the pockets 9 are formed, at their upper edges with spaced pairs of bracket-like lugs 10 between which the ears 6 of the respective rails 1 are received. The lugs 10 comprise members which are angular in side 95 elevation, and the inner or vertical walls thereof, in a line with the lower straight walls of the horizontal portions thereof have rounded depressions 11 which are in a line with the rounded openings 7 in the ears 100 6. Through the openings 7 there are passed pins 12 that contact with the horizontal portions of the lugs or brackets 10 and hold the rails on the chair.

The lugs 3 of the rails are received one in 105 each of the pockets 9 of the chair, and the opposite edges of the lugs are contacted by the rail engaging members illustrated in detail in Figs. 6 and 7 of the drawings. These members, when assembled provide a rocking 110 cradle which not only holds the rails against downward movement but which effectively

prevents the creeping of one rail against the other rail, so that danger incident to such contingencies will be effectively overcome. The main member of each of the cradles is indicated broadly by the numeral 13. This member includes a round head 14 that is received in a rounded concavity 15 in the inner wall of the pocket 9, at each end of the chair 8. The numeral 16 designates a shaft or pin that passes through a central opening in the head of the member 13, and the numeral 16' designates a projecting jaw on the inner face of the head which is received in the concaved depression 5 of the lug 3 on the respective rails 1. The body portion of the member 13, below its jaw 16' has an inclined wall 17 which is designed to contact with the under face of the lug 3 when the rails are influenced by climatic changes or by the pounding pressure of the wheels thereon to cause the rails to move toward each other and which contacting engagement will limit the said movement of the rails in such direction, the parts being so constructed and arranged that such engagement will take place immediately before one of the rail ends contacts with the other, and it will be manifest that the pressure exerted between the jaw 16' and the concaved face of the lug will restrict the travel of one of the rails in the direction of the other rail. Thus the rails, while permitted a desired longitudinal movement incident to expansion or contraction are effectively prevented from having their ends contact with each other. The rails will be free to move in opposite directions, but such movement is also restricted, to a certain extent by the engagement of the concaved end 18 of a link 19 which is pivoted, as at 20 between arms 21 on the body portion of the members 13. It is to be noted that the pivots 16 and 20 are disposed a considerable distance beyond the ends of the lugs and that a movement of the member 13 will influence the link member 19 so that both of these members will at all times effectively contact with the opposite ends of the lugs 3 of the rails, and as a consequence the cradle members, in addition to serving as anti-creeping elements provide supporting means for the rails that will prevent the movement thereof in a downward direction and which will also simultaneously move with the rails, should the rails be resting above the chair.

The base 8 of the chair has flanges 22 and 23 at its edges. The flange 22 is of a materially less height than the flange 23, but is sufficiently elevated to contact with the outer flange of an angle plate 24. The flange 23 provides the outer wall of a pocket, the inner wall being provided by the webs of the rails adjacent to the said flange. In this pocket is a splice bar 25 that has its inner corners formed with projecting flanges in

the nature of nose portions 26 that contact with the webs of the rails as well as with the underface of the heads and with the base of the rails. Through the angle or fish plate 24, the webs of the rails and bar 25 pass bolts 27 that are engaged by nuts 28. The openings in the webs of the rails through which the bolts pass are elongated in the usual manner to permit of the longitudinal movement of the said rails incident to expansion and contraction.

Formed in a line with the base 8 at the central portion of the chair, and projecting outward from the flange 23 is a ledge plate 29. This plate has spike openings therethrough, and this plate as well as the base plate 8 rests on a tie 30. The tie, it will be noted is arranged directly below the meeting ends of the rails 1 and is positioned between the box-like members that provide the pockets 9 of the chair. The chair is secured to the tie by spikes 31 that pass through the openings 32 in the ledge plate, as clearly disclosed in Figs. 1 and 2 of the drawings.

It is believed that the foregoing description, when taken in connection with the drawings will clearly set forth the construction and advantages of the improvement to those skilled in the art to which the invention relates.

Having thus described the invention, what I claim is:—

1. Two rail ends having depending lugs, a rocking cradle below each lug composed of members pivotally supported beyond the ends of the lug and having portions that have a contacting engagement with the opposite ends of the lugs.

2. Two rails each having a depending lug, a rocking cradle below each lug comprising members which are pivotally supported below and to the opposite ends of the lugs and which have elements having a contacting engagement with the opposite ends of the respective lugs, and one of the respective elements disposed in the path of contact with the under face of the respective lugs.

3. Two rail ends each having a depending lug, a chair on which the rail ends rest, pivoted members carried by the chair having jaw portions to engage one end of the respective lugs, and pivoted elements carried by said jaw members engaging the second end of the respective lugs.

4. Two rail ends having each a depending lug, a chair on which the rail ends rest, a cradle carried by the chair below each lug, and each cradle comprising a pivoted member having a jaw to engage one end of the lug and a link pivoted to the jaw member to engage the opposite end of the lug.

5. Two rail ends having each a depending lug and a depending ear, a chair on which the rails rest, spaced brackets on the ends of the chair receiving therebetween the ears

- of the rails, elements passing through the ears and contacting with the under faces of the brackets, a cradle carried by the chair beneath each of the rail lugs, and including 5 a member which is pivoted to the chair and which has a jaw that engages one end of one of the respective lugs, and a pivoted member carried by the first mentioned member and engaging with the opposite end of 10 the respective lug.
6. Two rail ends each having a depending lug and a depending ear, each of the lugs having one of its ends concaved and its opposite end convexed, a chair on which the 15 rails rest having pockets receiving therein the lugs, cradles in said pockets, each including a headed member which is pivoted transversely in the respective pockets and which is provided with a jaw having a 20 rounded end to engage in the concaved end of the respective lugs, a link member pivoted to the outer end of the first mentioned member and having a concaved end to engage with the rounded end of the respective
- lugs, the lower face of each of the lugs being 25 in the path of movement of the first mentioned member of the respective cradles, and spaced brackets on the ends of the chair receiving therebetween the respective ears of the rails. 30
7. Two rail ends each having a depending lug and a depending ear, a chair member on which the rail ends rest, and said chair being centrally supported on a tie, said chair having its face provided with box-like de- 35 pressions forming pockets each for a cradle, said cradle comprising pivoted members each having a contacting engagement with the opposite ends of the respective lugs of the rails, flanges on the edges of the base 40 member of the chair, splice members contacting with said flanges and with the rails, securing means through the said splice members, the rails and one of said flanges, and a horizontal ledge projecting from one of 45 the flanges resting on and secured to the tie.

In testimony whereof I affix my signature.
ARTHUR J. WILKINS.
